Primary Examiner — Deanna L Fluegeman(74) *Attorney, Agent, or Firm* — Banner & Witcoff, Ltd.**CLAIM**

The ornamental design for a display screen with graphical user interface, as shown and described.

DESCRIPTION

FIG. 1 is a front view of a display screen with graphical user interface showing our new design; and,

FIG. 2 shows the display screen of FIG. 1 on a device. The broken line showing of the three squares and the icons in FIGS. 1-2, and of the remainder of a device containing the display screen in FIG. 2, is for environmental purposes only and forms no part of the claimed design.
